UNITED STATES PATENT OFFICE.

ANDREW C. ZWARICH, OF HOMESTEAD, PENNSYLVANIA.

POWER-TRANSMISSION DEVICE.

1,237,598.

Specification of Letters Patent. Patented Aug. 21, 1917.

Application filed April 11, 1917. Serial No. 161,175.

To all whom it may concern:

Be it known that I, ANDREW C. ZWARICH, a subject of the Czar of Russia, residing at Homestead, county of Allegheny, and State 5 of Pennsylvania, have invented certain new and useful Improvements in Power-Transmission Devices, of which the following is a specification.

This invention relates to power transmission device for driving machines, or for other purposes wherein found applicable, and has for its object to provide a device of such type, in a manner as hereinafter set forth, with means for changing an intermittent rotary motion into a continuous one, and is designed primarily as an improvement on the construction shown in Letters Patent No. 1,179,599, granted to me April 18th, 1916, and besides including the objects 20 and advantages set forth in said Letters Patent, further includes means, in a manner as hereinafter referred to, to increase the efficiency of the means for changing the intermittent rotary motion into a continuous 25 one.

Further objects of the invention are to provide a motor which is simple in its construction and arrangement, strong, durable, efficient in its use, readily set up and comparatively inexpensive to manufacture.

With the foregoing and other objects in view the invention consists of the novel construction, combination and arrangement of parts, as hereinafter more specifically described and illustrated in the accompanying drawing, wherein is shown an embodiment of the invention, but it is to be understood that changes, variations and modifications can be resorted to which come within the 40 scope of the claims hereunto appended.

In the drawings wherein like reference characters denote corresponding parts throughout the several views:

Figure 1 is a vertical sectional view of a 45 motor in accordance with this invention.

Fig. 2 is a vertical section on line II-II, Fig. 1.

Fig. 3 is a detail illustrating one of the driving elements.

Referring to the drawings in detail 1 denotes a stationary shaft provided intermediate its ends with a crank 2. The shaft 1 is mounted in a pair of uprights 3.

The reference character 4 denotes a closed 55 annular hollow casing provided with a pair of oppositely disposed lugs 5 which are ro-

tatably mounted upon the shaft 1. The casing 4 is termed a rotor.

The crank 2 is positioned within the rotor, and has rotatably mounted thereon a disk 6, 60 which is eccentrically disposed with respect to the rotor 4.

Loosely connected at their inner ends, as at 7, to the disk 6, as well as being arranged equi-distant, is a series of shifting elements 65 8, 9, 10 and 11. The outer ends of said elements 8 to 11 are loosely connected, as at 12, to the inner face of the body of the rotor 4. The outer ends of the shifting elements 8 to 11 are arranged equi-distant with respect 70 to each other and each of said elements consists of a contractible and expansible coil spring.

Fixed to one side of the rotor is a ratchet wheel 13 and to the other side a ratchet wheel 75 14, the latter being in a reversed position with respect to the former. Associated with the ratchet wheels are driving elements or actuating members each consisting of a lever 15 and a pivoted pawl 16. The levers 15 80 are connected with suitable operating devices as at 16a. Each ratchet wheel and its actuating member is termed a driving element and each is adapted to intermittently rotate the rotor. One driving element shifts 85 the rotor in one direction and the other in the opposite direction.

One of the lugs 5 is provided with a pulley or gear 17 whereby the rotor can be coupled with a machine or other device and 90 operate the same.

The shifting elements 8 to 11 are employed to change the intermittent rotor drive into a continuous one, that is to say, when the rotor is intermittently operated 95 by a driving element the shifting elements will successively expand and contract and during the contracting movement thereof cause the rotor to revolve. Such movement is had in view of the fact, that the disk 6, 100 is eccentrically disposed with respect to the rotor and that the inner ends of the shifting elements are off-center. When the shifting element 8 assumes the position illustrated in Fig. 1, it is completely contracted, and as the rotor revolves it is gradually expanded until it assumes the extended position as illustrated in connection with the element 10 of Fig. 1. On further movement of the rotor the shifting member is 105 contracted, as illustrated in connection with the member 11 of Fig. 1, and assists in re-

volving the rotor. In view of the foregoing arrangement as stated the intermittent impulse given the rotor by the driving element the rotor will be changed by the 5 action of the shifting elements into a continuous motion.

To increase the efficiency of the shifting elements, means is employed, to bend said elements at the center of each when each 10 of said elements assumes its normal contracted position and by such an arrangement the tension of such element is increased and under such circumstances its efficiency is also increased. The means just referred to consists of a series of pivoted tensioning devices, one for each shifting element, and each of said devices consists of a pivoted arm 18, having its outer end provided with a yoke 19, in which is pivotally mounted a 20 roller 20, the latter being capable of bearing against the central portion of a shifting element and bending said central portion to one side during the operation of the rotor, as shown in Fig. 1. The arm 18 is pivotally 25 connected to a lug 21 arranged in close proximity to the point of connection between the shifting elements and the rotor. Formed integral with and projecting from the arm 18 at an angle with respect thereto is a 30 coupling arm 22, which is connected with the shifting element as at 23, and acts as a means for coupling the arm 18 with that shifting element with which it is associated.

It will be assumed that the shifting element 8 is in the position shown in Fig. 1, as such element is contracted; the coupling arm 22 will move toward the outer end of the shifting element, and which swings the arm 18 toward the shifting element, the 40 roller 20 engages the shifting element and bends it at its center thereby increasing the tension of said element. As the rotor moves around, a tensioning device will be gradually moved away from the shifting element until 45 said device assumes the position as illustrated in connection with the shifting element 10, Fig. 1. As the rotor continues to move the tension device, due to the contracting of the shifting element, will be moved 50 toward said shifting element until the tensioning device assumes the position as shown in connection with the shifting elements 11 and 8, Fig. 1.

What I claim is:

55 1. A power transmission device comprising a crank shaft, a disk carried by the crank of said shaft, a rotor revolving upon

said shaft and having said crank arranged therein, means for intermittently rotating said rotor, and a series of expandable and 60 contractible pulling members arranged within said rotor and having their inner ends connected with said disk at equi-distant points and their outer ends connected to the inner face of the rim of the rotor at equi-distant points and providing means for changing the intermittent drive of the rotor into a continuous one, and tensioning devices for said pulling members.

2. A power transmission device comprising a crank shaft, a disk carried by the crank of said shaft, a rotor revolving upon said shaft and having said crank arranged therein, means for intermittently rotating said rotor, and a series of expandable and 70 contractible pulling members arranged within said rotor and having their inner ends connected with said disk at equi-distant points and their outer ends connected to the inner face of the rim of the rotor at equi-distant points and providing means for changing the intermittent drive of the rotor into a continuous one, and tensioning devices for said pulling members, and each of said devices pivotally connected with the rim of 75 the rotor and coupled with the pulling member.

3. A power transmission device comprising a crank shaft, a disk carried by the crank of said shaft, a rotor revolving upon 90 said shaft and having said crank arranged therein, means for intermittently rotating said rotor, and a series of expandable and contractible pulling members arranged within said rotor and having their inner ends 95 connected with said disk at equi-distant points and their outer ends connected to the inner face of the rim of the rotor at equi-distant points and providing means for changing the intermittent drive of the rotor 100 into a continuous one, and tensioning devices for said pulling members, and each of said devices pivotally connected with the rim of the rotor and coupled with the pulling member, and each of said devices including 105 a pivoted arm having a roller capable of bearing against the shifting element to bend it at its center.

In testimony whereof I affix my signature in the presence of two witnesses.
